FREDERICK G. JAHN, OF BROOKLYN, NEW YORK, ASSIGNOR TO INTERNATIONAL POSTAL SUPPLY COMPANY OF NEW YORK, OF BROOKLYN, NEW YORK, A CORPORATION OF NEW YORK.

TRIP FOR CANCELING-MACHINES.

1,134,271.

Specification of Letters Patent.

Patented Apr. 6, 1915.

Application filed October 23, 1912. Serial No. 727,384.

To all whom it may concern:

Be it known that I, FREDERICK G. JAHN, a citizen of the United States, and resident of Brooklyn, in the county of Kings and State of New York, have invented certain new and useful Improvements in Trips for Canceling-Machines, of which the following is a specification.

This invention relates to a canceling machine of the type commonly used for marking mail matter. These machines operate at high speed, in fact it is quite common to cancel a thousand letters in a minute.

It is evident that where a complete operation of the machine is performed in such a small fraction of a second that various problems of inertia arise, and it is not possible to produce a machine without taking these factors into account as forming a very important part of the action. This even affects the feed. For example a thick and heavy letter will not start as quickly as a light thin letter and the frictional surface of the paper varies with each piece presented. Many other conditions make the feeding problem a difficult one, so that it has been found in practice that the best results are secured by a rotary feed which permits the letters, cards or sheet to feed forward in a continuous procession, but without any attempt to secure absolute regularity in the feed. In other words, the sheets and cards are allowed to feed as best they can, following along either close together or more separated according to chance, and the printing part of the mechanism is adapted to be tripped when the sheet or card arrives at a certain point, and by the action of the sheet or card itself. This imposes special difficulties in the control of the printing and tripping mechanism. But without this, in view of the high speed of the sheet or card and its necessarily frail nature, and in view of the necessarily considerable inertia present in any printing mechanism, it is evident that the problem of so starting the printing mechanism into action and generally controlling its movement is bound to be a difficult one.

By the present invention an improved trip is provided which is adapted to operate at very high speed and with the frailest

sheets and cards such as checks, which have practically no stiffness or strength either edgewise or flatwise.

With this object in view the invention consists in the improved canceling machine as hereinafter set forth and claimed.

In the drawings:—Figure 1 is a plan view of a portion of a canceling machine embodying the principles of this invention. Fig. 2 is a side elevation of the same. Fig. 3 is a detail plan view partly in section, showing a sheet or card just arrived at tripping position. Fig. 4 is a similar view showing the sheet or card somewhat farther advanced. Fig. 5 is a vertical sectional view of the canceling mechanism. Fig. 6 shows the clutch in vertical section.

Constructions embodying the invention will include a suitable rotating power shaft or die hub on which the printing or marking roll is mounted.

The best constructions embodying the invention will include a continuously rotating gear 10 loose on a vertical axis, having a friction clutch as shown for example in Fig. 6. This friction clutch is shown composed of a pair of cork or similar friction disks 11, 12 pressed into contact with the side faces of the gear 10, and constrained between collars 13, 14 rotating with the printing roller 15 and its die hub 16.

As a means for keeping the friction disks in contact with the gear 10, a pin 17 is illustrated, the same being movable along the longitudinal axis of the die hub 16 in a slot thereof, and normally pressed against the collar 13, by a spring 19 and plunger 20. The tension of the spring 19 can be regulated by an adjustment screw 21 bearing on an intermediate plunger 22. With this construction the die hub may remain at rest while the gear 10 continues its normal rotation, and this condition is the normal one of the machine, the die hub being held stationary by a stop or trip mechanism.

Secured upon the die hub is a projection 25, and a desirable construction is illustrated in which a collar 26 having two flanges 27, 28 is secured upon the die hub, the upper flange 28 being cut away in part, as hereinafter described, to form a cam. To form this projection, a roller 25 is shown,

loose on a pin extending between the flanges 27 and 28, such pin being fixed therein. The die hub will of course rotate in any suitable bearings 30 and 31.

5 There will also be provided an arm co-operating with the projection 25 on the die hub to arrest the rotation of the die hub and hold the latter normally in a certain fixed position. For this purpose a construction 10 having a comparatively large freely rotatable disk or roller 33 on a swinging arm 34, is best adapted to the requirements, this disk intercepting the movement of the projection 25 so that the strain under normal conditions is in line with the pivot of 15 the arm 34 and there is no unbalanced force tending to displace the arm and permit the die hub to start into rotation. Means are however provided for swinging the arm 20 laterally when a card or sheet arrives at a certain point, and a slight lateral displacement of the arm creates an unbalanced force tending to further displace the arm and permit the die hub to rotate. The normal 25 position of the arm is shown in Fig. 1. The laterally displaced position of the arm is illustrated in Fig. 3, and the returned position of the arm preparatory to intercepting more than one complete rotation of the die 30 hub is shown in Fig. 4. The lateral displacement of the arm 34 just referred to, and its return to normal position are accomplished by the action of the machine, and the conditions mentioned in the 35 preliminary part of the specification are particularly important and controlling in this action. That is to say, the means for displacing the arm and returning it to normal position must take into account both the 40 very light and frail character of sheets such as bank checks, and also the very high rapidity with which these machines operate. The first condition makes only a very small tripping force obtainable when the sheet 45 arrives at a certain position so that any tripping lever must be very easily displaced, and the second condition makes it necessary to have a powerful and positive action of the machine parts since the inertia of metal 50 parts which move back and forth in a very small fraction of a second is very considerable. Any mere springs cannot be relied upon for the moving force since springs have only a certain force and at high speeds 55 the mere inertia of the metal parts of the machine may be so great as to make it impossible for any ordinary spring, unless exceedingly heavy and powerful, to furnish the necessary force. It is therefore part of 60 the purpose of the present invention to eliminate heavy springs, this being done particularly in view of the fact that any spring acts with a force which being constantly exerted, makes it difficult for any frail sheet 65 or card to produce the actuation of the

machine. Any spring imposes resistance not only by its own tension, but also by putting a strain on the pivots and guides which increases their friction directly, and also indirectly by making a heavier lubricant necessary. The springs suggested or employed by the present application are very light springs with practically no force, since by the nature of the actions in which these springs are involved the smallest possible force will be sufficient even for the highest speeds of the machine.

Constructions embodying the invention will include a cam 28' acting on an arm 36 preferably forming part of the swinging arm 34 carrying the roller 33. The cam 28' is so cut away as to permit the arm 36 to swing laterally only at a certain position of the die hub, namely its normal position of rest. It will be observed from Fig. 1 that the cam is cut away to permit the lateral movement of the arm in this position. The lateral movement of the arm is commenced as later described by a check or sheet or card, and after its commencement 85 the action of the projection 25 against the surface of the disk or roller 33 throws the arm still further out with a positive and powerful application of force due to the force of the rotation of the die hub itself. 90 The arm therefore moves laterally with promptness and certainty but it has no sooner moved far enough to permit the projection 25 to escape and the die hub to start in rotation than the cam 28' comes into 100 action and throws the arm back again with just as great positiveness and certainty to its original position. The whole displacement and return is therefore accomplished in a very small fraction of a second, and 105 during a very small part of the rotation of the die hub. Thereafter the roll or disk 33 is not only in a position to intercept the rotation of the die hub after its single 110 printing revolution, but is furthermore locked in this intercepting position by a concentric peripheral surface of the cam which lies against the arm. It will be particularly noted that it is locked against any rebound.

115 Thus, the following functions are provided for: 1st, a very small displacement of the arm is produced by the sheet or card to be canceled. 2nd, this initial slight displacement is immediately and by a positive 120 means completed to a sufficient extent by the starting of the die hub. 3rd, the arm is instantly and positively returned before the die hub has completed more than a fraction of its rotation. 4th, the arm is positively 125 returned to the position where it intercepts more than one rotation of the die hub and is locked in this position. Thus all of the conditions pertaining to high speed are satisfied and there is no reliance placed on 130

springs. A very light spring may be used to assist in the control of the arm, but its power is inappreciable.

Consideration will now be given to the 5 conditions which permit the tripping to be done with a very frail check or card.

It is understood that the sheets or cards travel edge up with considerable speed, and are forwarded between rapidly revolving 10 rolls. Between a pair of such rolls 40 projects a finger or trip 41, which is connected to swing or move in any suitable manner and most conveniently by a rock shaft 42 carrying an arm 43 and on which the finger 15 is mounted. This rock shaft 42 turns in a suitable fixed bearing 44. It is part of the action of this trip or finger to be displaced in the direction of its length, and for this 20 purpose an improved sliding connection has been provided which permits a very free movement of the finger, and by a character of guide which is protected against dust and dirt and the evaporation of lubricant. In this way a very free movement of the 25 finger will be obtained, and since the finger is very light and has only a small movement, a very light spring may be used to control its movement. As particularly shown in Figs. 3, 4 and 5 the finger carrying arm has 30 an upwardly extending flattened portion 45 which is grooved at 46 on one side. The finger itself is undercut so as to be of generally inverted U shape, and has a guide way 47 fitting into the groove 46 so as to 35 furnish a guide for reciprocation in the direction of its length. By virtue of the U shape of the finger, and further by reason of thin side plates 48 on the finger, the latter is virtually housed against dust and 40 dirt and the evaporation of oil. A small spring 50 connects a stud 51 on one end of the finger with a relatively fixed stud 52 on the finger carrying arm.

It will now be imagined that a thin sheet 45 or card is passing rapidly through the machine, and arrives in the bight of the two rolls 40 at the location of the finger 41. At this instant the leading edge of the paper is stiffened by the rolls and is in the best 50 condition to exert a force on the finger which it does momentarily. The direction of this force is such that there is no tendency put upon the finger to yield backward in the direction of its length, and accordingly 55 the finger can only swing in the path of movement of the check, carrying with it the arm and trip. In the case of frail checks the finger may be only slightly moved in this way, before the check loses its stiffness 60 by reason of its projection too far out of the rolls 40. But since the arm is rotated positively after having once been started the finger is drawn forward out of the way of the advancing check immediately after it 65 has been started, and the check is free to

move on unimpeded. By the time the arm has been swung fully back and has commenced its positive return, the sheet has advanced to a position where its side face is opposite the finger, and under these circumstances the finger may yield inwardly in the direction of its length under the new forces now put upon it, by bearing against the side face of the check or sheet or card. As the finger is very light and its spring is 70 very light it follows that the finger is thus caused to yield and it remains thrust backward in the direction of its length until the sheet or card has passed. Its spring then acts to project it forward in the path of the 75 next advancing sheet or card, which movement is only a very small fraction of an inch and is easily accomplished by a light spring on account of the small distance of movement and the smallness and lightness 80 of the finger to be moved. Thus by the return of the finger in this way the entire mechanism is restored to its original and normal condition and is ready for a repetition 85 of the actions as already described. 90

What is claimed is:—

1. In a canceling machine, a finger carrying member, a finger thereon, a die hub having a projection, an arm adapted to be displaced by said finger carrying member and 95 normally intercepting said projection, and means actuated by a moving part of the mechanism for positively returning said arm when the latter has been displaced.

2. In a canceling machine, a finger carrying member, a finger thereon and independently movable in the direction of its length thereon, a die hub having a projection, an arm adapted to be displaced by said finger carrying member and normally intercepting 100 said projection, said die hub and arm co-operating to positively continue the displacement of said arm and thereafter return it to 105 normal position.

3. In a canceling machine, a finger carrying member, a finger thereon, a die hub having a projection, an arm adapted to be displaced by said finger carrying member and normally intercepting said projection, said die hub and arm co-operating to 110 positively continue the displacement of said arm and thereafter return it to normal position. 115

4. In a canceling machine, a finger carrying member, a finger thereon, a die hub having a projection, an arm adapted to be displaced by said finger carrying member and having a roller intercepting said projection, and means actuated by a moving part of the mechanism for positively returning said arm when the latter has been 120 displaced.

5. In a canceling machine, a finger carrying member, a finger thereon, a die hub having a projection, an arm adapted to be displaced by said finger carrying member

and normally intercepting said projection, said arm being forced laterally by the movement of said projection, and means actuated by a moving part of the mechanism for 5 positively returning said arm when the latter has been displaced.

6. In a canceling machine, an oscillating finger carrying member, a finger longitudinally slidable thereon, a die hub, an arm intercepting the rotation of said die hub, means for returning said arm when it has been displaced, and a yielding means for permitting the finger to yield against the flat face of the sheet fed during such return 10 movement of the arm, and projecting such finger at the termination of such return movement.

7. In a canceling machine, a finger carrying member, a finger yieldable thereon, a die hub, an arm having a roller intercepting the rotation of said die hub, positive means actuated by a moving part of the mechanism for returning said arm when it has been displaced, and a yielding means for 15 permitting the finger to yield against the flat face of the sheet fed during such return movement of the arm.

8. A canceling machine, a finger carrying member, a finger longitudinally movable thereon, a die hub, an arm intercepting the rotation of said die hub, a cam for positively returning said arm when it has been displaced, means for locking the arm in returned position, and means for permitting 30 the finger to move tangentially across the flat face of the sheet fed during such return movement of the arm.

9. In a canceling machine, a finger carrying member, a finger independently movable thereon, in the direction of its own length, a die hub, an arm intercepting the rotation of said die hub, means actuated by the die hub for continuing the movement of 40

the arm after the same has been displaced from its initial position, means for returning said arm when it has been displaced, and means for permitting the finger to move tangentially across the flat face of the sheet fed 45 during such return movement of the arm.

10. In a canceling machine, a finger carrying member, a finger longitudinally slidable thereon, a spring for lightly projecting said finger, a die hub, an arm intercepting the rotation of said die hub, and a cam on said die hub for returning said arm when 50 it has been displaced, whereby the finger moves tangentially across the flat face of the sheet fed during such return movement of the arm.

11. In a canceling machine, a finger carrying member, a finger movable thereon, a die hub having a cam with a concentric peripheral portion, an arm intercepting the rotation of said die hub, and an arm engaging said cam and the concentric peripheral 55 portion thereof, whereby said arm is positively returned and locked in its returned position.

12. In a canceling machine, a finger carrying member, having an upward flattened extension, and a finger having an inverted U shape and housed to cover said extension and sliding thereon.

13. In a canceling machine, a finger carrying member, having an upward flattened 75 extension, a finger having an inverted U shape and housed to cover said extension and sliding thereon, and a spring for normally projecting said finger.

Signed at New York in the county of New 80 York and State of New York this 21st day of October A. D. 1912.

FREDERICK G. JAHN.
